CAR UNDERFRAME STRUCTURE

Edwin P. Moses, White Plains, N. Y.

Application June 6, 1936, Serial No. 83,945

10 Claims. (Cl. 105—415)

The invention relates to railway rolling stock and comprises features of vehicle underframe construction particularly adapted for use in hopper cars although not limited to such application.

The invention consists primarily in center sill, bolster, and associated structure whereby various accessories usually made separately from the underframe and forming no part thereof are combined with the underframe structure.

One object of the invention is to reinforce the center sill bolster and center plate structure as is necessary for heavy service requirements to which hopper cars, for example, are subjected without unduly increasing the weight of the structure.

Another object of the invention is to construct and locate equipment such as air reservoirs, brake cylinders, etc. so that space limitations may be accommodated and, preferably, so that this equipment may contribute to the framing.

Structure embodying the present invention and other structure having the same general objectives is disclosed in the copending application of the present applicant, Serial No. 734,080, filed July 7, 1934, now Patent No. 2,035,762, of which the present application is in part a division and continuation.

These and other detailed objects indicated below are obtained by the structure illustrated in the accompanying drawings, in which—

Figure 1 is a top view of one longitudinal half of a hopper car underframe structure embodying the invention.

Figure 2 is a side elevation of the same, a portion being sectioned to more clearly illustrate a detail of the structure.

Figure 3 is a vertical transverse view and section taken on the line 3—3 of Figure 1.

Figure 4 is a longitudinal section taken on the line 4—4 of Figure 1.

Figure 5 is a detailed transverse section taken on the line 5—5 of Figure 4.

Preferably the underframe comprises a single unitary construction such as a one-piece casting, although this preferred form is not essential for most features of the invention. Such a casting is illustrated in the drawings and includes box-shaped center sill structure having a top wall 1, side walls 2, and a bottom wall 3 with substantial openings 4 for lightening the structure and facilitating production of the casting. This sill structure extends from end to end of the car with its forward portion comprising draft sills 5

with suitable rib openings 6 for receiving draft gear keys (not shown).

Transverse vertical webs 7 brace the center sill structure at intervals and preferably these webs are apertured to receive piping 8, the marginal portions of the apertures including brackets 9 for mounting the piping either directly or through clamps such as indicated at 10.

Bolster structure indicated generally at 11 merges with the center sill structure and extends transversely thereof to the sides of the car. At the intersection of the bolster and center sill, lower wall 3 is depressed as at 12 to form center plate structure arranged for interengagement in the usual manner with the center plate of a supporting truck (not shown). An upstanding tubular member 13 extends upwardly from the central portion of the center plate structure, rigidifying the latter and providing a mounting for the king pin (not shown) which connects the underframe and truck.

A vertical transverse web 14 at the rear of center plate 12 forms a part of the bolster structure and reinforces the sill structure at this point. An upright rib 15 extends between member 13 and web 14 and into the depressed center sill forming portion of bottom wall 3. A draft gear stop block 16 extends upwardly at the front of the center plate structure with its sides spaced from the adjacent side walls 2 of the center sill. Stop block 16 is connected with member 13 by a central vertical rib 17 corresponding generally to rib 15 and diagonal ribs 18 extend from block 16 rearwardly and downwardly into the depressed center plate forming portion of the bottom wall 3 bracing elements 12 and 16 from each other.

The bolster structure at the sides of the center sill structure is of general I-shaped cross-section having a vertical web 19, a top flange 20 substantially horizontal from end to end, and a bottom flange 21 which is inclined upwardly and outwardly from the center plate to the side of the car. An air reservoir 22 is located in one of the angles formed by the bolster and draft sill structure and utilizes the adjacent draft sill as an end wall and the adjacent portion of web 19 as an element of the side wall. The adjacent portion 23 of the inclined bottom flange 21 of the bolster merges with the outer end of the reservoir and the reservoir constitutes a substantial bracing structure across the angle between the bolster and draft sill.

Preferably a horizontal bracket 24 projects from the forward portion of the air reservoir and mounts a diagonal brace 25 extending to the

forward corner of the built-up platform structure (not shown) carried by the underframe. An upright web 26 intermediate the ends of reservoir 22 braces the walls of the latter and receives the thrusts transmitted to bracket 24.

A gusset 27 extends between the bolster and draft sill at the side of the latter opposite to reservoir 22 and a brake cylinder 28 is carried by this gusset, and the cylinder and its support 10 29 are shown as cast integral with the remainder of the underframe. Gusset 27 includes a bracket 32 corresponding to bracket 24. Between cylinder 28 and reservoir 22 is a rectangular bracket 30 for mounting the air brake valve 31, and bracket 30 also is preferably formed as part of the underframe casting.

The above described structure comprises an effective underframe for hopper cars and the relation of the underframe to the sloping end 20 floors and hopper structure is indicated by the broken lines H in Figure 2. The provision of complete separately formed reservoir and brackets therefor on the underframe is avoided by the unitary structure. The arrangement of the center plate is simplified and the elements of the center plate and the reinforcement thereof also constitute elements of the center sill and draft stop structure.

As previously indicated, the casting of the elements in one piece is not essential to all features of the invention and other modifications of the invention may be made without departing from the spirit of the invention and the exclusive use of such modifications as come within the scope 35 of the claims is contemplated.

What is claimed is:

1. A railway vehicle underframe integral structure including intersecting center sill and bolster members, and a fluid reservoir between said bolster member and the end of the underframe, said reservoir having walls merging with and forming a part of the upright webs of said bolster member and center sill members.

2. Structure as specified in claim 1 which also 45 includes a bracket projecting from the reservoir for mounting a platform framing member.

3. Structure as specified in claim 1 which also includes a bracket projecting from the reservoir intermediate the ends of the latter for mounting a platform framing member, there being a reinforcing web extending across said reservoir between said bracket and bolster structure.

4. In a railway car underframe, a center sill, a bolster having a vertical web extending from 55 said center sill to the side of the car, there being a lateral flange projecting from the lower portion of said web at one side thereof, an air reservoir located at the opposite side of said web and extending along the same towards the side 60 of the car but terminating short of the end of

said bolster, and the lateral flange on the opposite side of said web extending inwardly from the end of the bolster and merging with the end of said reservoir.

5. A railway vehicle underframe rigid one-piece structure comprising intersecting center sill and bolster members, a fluid pressure brake cylinder and a fluid reservoir in the respective corners between said members and merging therewith, and an air brake valve mounting merging 10 with said center sill between said cylinder and reservoir.

6. In a railway vehicle underframe, a bolster having an upright web, a draft sill extending from said bolster towards the adjacent end of the underframe, and a fluid reservoir located between said bolster and said underframe end and having a portion of its wall structure formed by said bolster web.

7. In a railway vehicle underframe, a bolster 20 having an upright web, a draft sill extending from said bolster towards the adjacent end of the underframe, and a fluid reservoir located between said bolster and said underframe end and having a portion of its wall structure formed 25 by said bolster web and draft sill.

8. In a railway vehicle underframe, a bolster, a draft sill extending from said bolster towards the adjacent end of the underframe, and a fluid reservoir located between said bolster and said underframe end and having a portion of its wall structure formed by said bolster, said reservoir being constructed and arranged to mount a diagonal corner brace at a point spaced from said bolster and to transmit thrust from the same to 35 said bolster independently of other framing members.

9. In a railway vehicle underframe, a bolster, a draft sill extending from said bolster towards the adjacent end of the underframe, and a fluid 40 reservoir located between said bolster and said underframe end and having a portion of its wall structure formed by said bolster, said reservoir being constructed and arranged to mount a diagonal corner brace at a point spaced from said 45 draft sill and to transmit thrust from the same to said draft sill independently of other framing members.

10. In a railway vehicle underframe, a bolster, a draft sill extending from said bolster towards the adjacent end of the underframe, and a fluid reservoir located between said bolster and said underframe end and having a portion of its wall structure formed by said bolster and draft sill, said reservoir being constructed and arranged to 55 mount a diagonal corner brace at a point spaced from said bolster and draft sill and to transmit thrust from the same to said bolster and draft sill independently of other framing members.
